HARRY F. WATERS, OF NEW YORK, N. Y.

METHOD OF AND MEANS FOR PRODUCING PIPE-ORGAN MUSIC

Application filed October 30, 1929. Serial No. 403,425.

This invention relates generally to methods and means for producing pipe organ music and more specifically to an improved method of and means for producing pipe organ music with the aid of a mechanical playing apparatus, the predominant object of the invention being to provide a method and means whereby either a piano player roll or an organ player roll may be employed in producing pipe organ music mechanically.

It is very well known that prior to this invention organ player rolls have been employed with mechanical organ players for producing pipe organ music. These organ rolls were so made that the organs were completely played by mechanical means; that is to say, the organ rolls referred to not only operated sound producing elements of the organ but said organ rolls were provided with perforations which caused tablets of the organ to be pulled down and performed other operations which an organist is required to perform in playing a pipe organ. A pipe organ played by a mechanical player with the aid of an organ roll is very efficiently and beautifully played, but unfortunately the supply of organ rolls is rather limited when compared with the anticipated demand for rolls for playing pipe organs.

Also prior to this invention efforts have been made to play pipe organs with the aid of piano player rolls but in the use of such rolls notes of only one manual were employed, the result being a monotonous, unmusical sounding of the solo notes only of the pipe organ.

Due to the fact that there is available a very great supply of piano rolls I have evolved the improved method and means disclosed herein, which briefly stated involves, (1), producing a mechanical player for pipe organs which may be actuated by piano player rolls, and (2), producing a mechanical player for pipe organs which may be actuated either by piano rolls or organ player rolls.

In following out my improved method I employ a mechanical player of the type heretofore used in the utilization of organ player rolls for playing a pipe organ. The note selecting mechanism of this mechanical

player, and the other mechanisms of the player which cooperate with elements of the pipe organ, are connected to the various elements of the pipe organ so that the pipe organ is played in the manner common to the use of mechanical organ players employing organ rolls. To provide for the use of piano rolls in playing the pipe organ, however, I electrically wire the note selecting mechanism of the mechanical player in a novel manner; that is to say, I arbitrarily select a point where a split will occur in the electrical wiring of the note selecting mechanism of the mechanical player and I electrically connect the note selecting mechanism above said split to the solo sound producing elements of the pipe organ, and electrically connect the note selecting mechanism below such split to the accompaniment sound producing elements of the pipe organ. With respect to the location of the split referred to I find that middle C of the note selecting mechanism of the player is the logical point for said split, inasmuch as most piano rolls are cut with the solo and accompaniment parts separated at middle C, but I do not limit myself to such location of the split.

In addition to wiring the note selecting mechanism of the mechanical player in the manner described, I also wire the accompaniment portion of said note selecting mechanism so as to provide an automatic bass accompaniment, such wiring of a keyboard or other note selecting mechanism of a pipe organ being very generally understood by persons familiar with the art to which this invention belongs, and involves so wiring the accompaniment side of the note selecting mechanism of the mechanical player that the note selecting element on the accompaniment side which is lowest in the scale of those actuated will, because of the electrical wiring scheme, actuate a note selecting element an octave lower in the scale than the first mentioned lowest note selecting element. The bass note selecting element so actuated may be connected to sound any desired number of bass notes, depending on the number of stop tablets employed, and the electrical wiring associated with lowest oc.

tave of the note selecting mechanism may be doubled back if desired to note selecting elements of a higher octave.

A mechanical player constructed and operated in accordance with this invention may be arranged to be operated by piano rolls only and when this is so no unusual problems will be presented, the note selecting mechanism of said player being wired in the manner described to operate the solo and accompaniment sound producing elements of the pipe organ, and the accompaniment side of the note selecting mechanism of the player being electrically wired to provide the automatic bass accompaniment. However, when the mechanical player is arranged to be operated by either a piano player roll or an organ player roll it will be necessary to provide a system selecting means which may be operated manually to place in operative condition the system actuated by a piano player roll or the system actuated by an organ player roll. This system selecting means may take various forms, for instance, it may comprise two separate systems of electric wiring adapted for cooperative association with the piano player rolls and the organ player rolls respectively, in which event a switch will be provided which may be thrown to place one or the other system in operation. Also, if desired, the system selecting means may be mechanical in form, one type of which would be a slidable element provided with one system of perforations to which tubes leading from the pipe organ elements actuated by the piano player rolls are connected, and a second system of perforations to which tubes leading from the pipe organ elements actuated by the organ player rolls are connected. When it is desired to utilize one or the other type of roll in playing the associated pipe organ the slidable element may be moved to bring the perforations of the desired system into cooperative position with respect to the apertures of the tracker bar of the mechanical player and by so positioning the slidable element only the desired system will be rendered operative.

Figure 1 is a schematic view of the wiring arrangement of a mechanical player electrically wired to play piano player rolls.

Figure 2 is a fragmentary diagrammatical view illustrating one form of the system selecting means employed in following out my improved method.

In Figure 1 of the drawing A designates diagrammatically the eighty-eight note selecting elements of a player designed to play standard piano player rolls and the line B designates the split in the wiring leading from said elements, said split, as hereinbefore stated preferably being located approximately at middle C of the musical scale. D designates the electrical conductors which

lead from the note selecting elements at the right of the split B, and E designates the electrical conductors which lead from the note selecting elements at the left of said split B. As already stated herein the conductors D are electrically connected to operate the solo sound producing elements of the organ while the conductors E are electrically connected to operate accompaniment sound producing elements of the organ. Also the electrical conductors F constitute parts of the electrical wiring system which provide the automatic bass accompaniment referred to herein, but as this wiring arrangement is quite complicated and is well understood by persons familiar with the art to which this invention belongs it has not been illustrated in detail.

In the use of a piano player roll with a mechanical organ player having the note selecting mechanism electrically wired as illustrated in Figure 1 very good results are obtained inasmuch as solo and accompaniment renditions on the pipe organ are derived. This may be accomplished, for instance, by pulling down a string tablet on the solo side of the organ and a flute tablet on the accompaniment side of the organ. The result would be a string solo accompanied by a flute, and it would be obtained with the use of a roll cut to play on one keyboard or manual only, and considerably more variety and expression is derived than was possible when piano player rolls were employed heretofore for playing pipe organs. In playing a pipe organ with the aid of a piano player roll in accordance with my invention the tablets must be pulled down manually as piano player rolls do not include perforations for performing these operations but in spite of this very greatly improved results are obtained over those realized heretofore in connection with the use of piano player rolls for playing pipe organs.

In Figure 2 I illustrate one means for selecting one or the other system for operation when the mechanical player is arranged to be operated by either a piano player roll or an organ player roll. This form includes a stationary perforated member 1 adjacent to which a slidable element 2 is positioned. 3 designates the tracker bar of a mechanical player, the perforations 4 formed through the tracker bar being connected by suitable tubes 5 to similarly spaced perforations 6 in the stationary member 1. The slidable element 2 is provided with two sets of perforations, the perforations of one set being designated by the reference character 7 and those of the other set being designated by the reference character 8. The perforations 7 are connected by means of suitable tubes 9 to the elements of the organ actuated by an organ player roll and the perforations 8 are connected by suitable tubes 10 to the elements of the pipe organ actuated by a piano player roll. When it is desired to use an organ play-

er roll or a piano player roll in playing an organ the slideable element 2 may be moved longitudinally of the stationary member 1 to bring the perforations 7 or 8 into registration with the perforations 5 in the stationary member 1, whereby the system to which the roll being used relates is placed in an operative condition.

I claim:

1. The herein described method of producing music mechanically with the aid of an electrically operated pipe organ having a mechanical player associated therewith, which comprises wiring the note selecting mechanism of the mechanical player so that a split is provided in the electrical wiring thereof with the note selecting means above such split electrically wired to solo sound producing elements of the organ and the note selecting means below the split electrically wired to accompaniment sound producing elements of the organ, and utilizing a piano player roll for actuating the note selecting means of the player.
2. The herein described method of producing music mechanically with the aid of an electrically operated pipe organ having a mechanical player associated therewith, which comprises wiring the note selecting mechanism of the mechanical player so that a split is provided in the electrical wiring thereof with the note selecting means above such split electrically wired to solo sound producing elements of the organ and the note selecting means below the split electrically wired to accompaniment sound producing elements of the organ, and utilizing a piano player roll or an organ player roll for actuating the note selecting means of the player.
3. The herein described method of producing music mechanically with the aid of an electrically operated pipe organ having a mechanical player associated therewith which comprises wiring the note selecting mechanism of the mechanical player, so that a split is provided approximately at middle C in the electric wiring thereof with the note selecting means above such split electrically wired to solo sound producing elements of the organ and the note selecting means below the split electrically wired to accompaniment sound producing elements of the organ, and utilizing a piano player roll for actuating the note selecting means of said player.
4. The herein described method of producing music mechanically with the aid of an electrically operated pipe organ having a mechanical player associated therewith which comprises wiring the note selecting mechanism of the mechanical player, so that a split is provided approximately at middle C in the electric wiring thereof with the note selecting means above such split electrically wired to solo sound producing elements of the organ and the note selecting means below the split electrically wired to accompaniment sound producing elements of the organ, and utilizing a piano player roll or an organ player roll for actuating the note selecting means of the player.

the split electrically wired to accompaniment sound producing elements of the organ, and utilizing a piano player roll or an organ player roll for actuating the note selecting means of said player.

5. The herein described method of producing music mechanically with the aid of an electrically operated pipe organ having a mechanical player associated therewith, which comprises wiring the note selecting mechanism of the mechanical player so that a split is provided approximately at middle C with the note selecting means above such split electrically wired to solo sound producing elements of the organ and the note selecting means below the split electrically wired to accompaniment sound producing elements of the organ, electrically wiring the note selecting means of the player to provide an automatic bass accompaniment, and utilizing a piano player roll for actuating the note selecting means of said player.

6. The herein described method of producing music mechanically with the aid of an electrically operated pipe organ having a mechanical player associated therewith, which comprises wiring the note selecting mechanism of the mechanical player so that a split is provided approximately at middle C with the note selecting means above such split electrically wired to solo sound producing elements of the organ and the note selecting means below the split electrically wired to accompaniment sound producing elements of the organ, electrically wiring the note selecting means of the player to provide an automatic bass accompaniment, and utilizing a piano player roll or organ player roll for actuating the note selecting means of said player.

7. The herein described method of producing music mechanically with aid of an electrically operated pipe organ having a mechanical player associated therewith, which comprises wiring the note selecting mechanism of the mechanical player so that a split is provided in the electrical wiring thereof with the note selecting means above such split electrically wired to solo sound producing elements of the organ and the note selecting means below the split electrically wired to accompaniment sound producing elements of the organ, utilizing a piano player roll or an organ player roll for actuating the note selecting means of the player, and providing means for selectively connecting the note selecting means actuated by the piano player roll, or the note selecting means actuated by the organ player roll with the sound producing elements of the pipe organ.

8. The herein described method of producing music mechanically with aid of an electrically operated pipe organ having a mechanical player associated therewith,

- which comprises wiring the note selecting mechanism of the mechanical player so that a split is provided in the electrical wiring thereof with the note selecting means above such split electrically wired to solo sound producing elements of the organ and the note selecting means below the split electrically wired to accompaniment sound producing elements of the organ, electrically wiring the note selecting means of the player to provide an automatic bass accompaniment, utilizing a piano player roll or an organ player roll for actuating the note selecting means of the player, and providing means for selectively connecting the note selecting means actuated by the piano player roll, or the note selecting means actuated by the organ player roll with the sound producing elements of the pipe organ.
9. A mechanical player for pipe organs including a plurality of note selecting elements, electrical conductors leading from said note selecting elements to a pipe organ, certain of said electrical conductors leading to solo sound producing elements of the pipe organ and others of said electrical conductors leading to accompaniment sound producing elements of said pipe organ, and a piano player roll of standard arrangement for actuating said note selecting elements.
10. A mechanical player for pipe organs including a plurality of note selecting elements, electrical conductors leading from said note selecting elements to a pipe organ, certain of said electrical conductors leading to solo sound producing elements of the pipe organ and others of said electrical conductors leading to accompaniment sound producing elements of said pipe organ, an electrical wiring system associated with the last mentioned conductors for providing an automatic bass accompaniment, and a piano player roll of standard arrangement for actuating said note selecting elements.

In testimony whereof, I have hereunto set my hand.

HARRY F. WATERS.
